UNITED STATES PATENT OFFICE.

GEORGE F. OCHS, OF NEWARK, NEW JERSEY.

AIRSHIP.

1,337,409.

Specification of Letters Patent. Patented Apr. 20, 1920.

Application filed January 27, 1919. Serial No. 273,388.

To all whom it may concern:

Be it known that I, GEORGE F. OCHS, a citizen of the United States of America, residing at Newark, in the county of Essex and 5 State of New Jersey, have invented new and useful Improvements in Airships, of which the following is a specification.

The principal purpose of the invention is to provide a new and novel form of airship 10 having buoyant element for maintaining it aloft, and means for driving it forward, means for causing it to raise vertically quickly and on an even keel and means for lowering it quickly and likewise on an even 15 keel. To this end the invention comprises a car suspended from a buoyant element designed to receive and hold a light gas or heated air, and longitudinally disposed tubular members positioned two on either side 20 of the buoyant element with one adjacent the bottom thereof, and the other adjacent the top, other tubular members disposed vertically with reference to the buoyant element, and propellers and driving elements 25 therefore mounted in one end of each tube, so that they may eject a stream of air from the remaining ends of the tubes for the purpose of driving the buoyant element forward, raising it or causing it to descend.

30 The driving elements for propellers are controlled from within the car, thereby making it possible for an operator to cause the buoyant element to ascend, descend or to move forward as is desired.

35 While illustrated and described in a specific embodiment the invention is not to be restricted to such embodiment. Actual practical application may suggest certain desirable changes or alterations, and the 40 right is claimed to make any which do not deviate from the scope of annexed claims.

The same numerals of reference designate the same parts throughout the several figures of the drawing, wherein:

- 45 Fig. 1 is a view in side elevation.
Fig. 2 is a longitudinal sectional view through the structure shown in Fig. 1.
Fig. 3 is a section on the line 3—3 of Fig. 1.
50 Fig. 4 is a section on the line 4—4 of Fig. 1.
Fig. 5 is a section on the line 5—5 of Fig. 1.

Fig. 6 is a horizontal sectional view through the car. 55

As shown, the invention comprises a car "A," which is suitably suspended from a buoyant element "B" in the form of a hollow cylindrical member terminating in conical ends 1. This hollow cylindrical member is designed to receive gas or heated air. On top of the cylindrical member or buoyant chamber B, there is a pop valve 2, whose purpose is to relieve the pressure interior to the buoyant chamber when it exceeds a predetermined amount. The buoyant chamber B is made preferably of light sheet metal, although any other acceptable material may serve the purpose. 60

On each side of the cylindrical portion 70 of the chamber B, there is carried a pair of tapering tubular members 3, tapering in the direction of the length of chamber B. On each side one of these members is adjacent to the top of chamber B, and the other adjacent to the bottom. The larger ends of the tubular members 3 are at the forward end of the airship and in these larger ends there are mounted the transverse members 4 in which there are journaled shafts 5, 80 which on one end carry propellers 6 and on the other ends operatively connect with driving motors 7, these motors being preferably electrically driven. At intermediate points in their length, the tubular members 85 3 are formed with circular side openings 8, which provides side intakes for fans 9 direct-connected to motors 10.

Adjacent the line of junction of the conical ends which, with the body portion of 90 the chamber B, there are vertically disposed tubular members 11. These tubular members also taper in the direction of their length, passed directly through the body portion of the chamber B, but adjacent the 95 sides and have their upper or smaller ends protruding from the top of said chambers. In their lower ends there are carried transversely disposed members 12, each of which support a rotatable shaft 13 direct-connected to a driving motor 14 and carrying at one end a propeller blade 15.

Adjacent to tubular members 11 there are other tubular members 16 also passing through the body portion of the chamber B, 105 but adjacent its sides. These tubular mem-

bers 12 also taper in the direction of their length but are disposed with the small ends projecting from the bottom of chamber B, leaving the larger ends projecting above the top of said chamber. In the top ends of these tubular members 16 there are mounted the transverse members 17, in which shafts 18 are journaled, the latter being connected as shown, to driving motors 19 and carrying propellers 20.

Interior to the car A the means for operating the motors 7, 10, 14 and 19 are carried and these means comprise an engine 21 preferably of the internal combustion type with revolving cylinders such as the "Gnome" which is operably connected to an electric generator 22 by means of a belt 23. Supply means 24 lead from this generator 22 to the controllers 25, which are three in number, *a*, *b* and *c* and which are connected in parallel with the generator. The motors 7 and 10 are electrically connected with one of the controllers 25 and they may be either serially connected or grouped in parallel with each other. The motors 14 are either serially connected or grouped in parallel with one of the other controllers and the motors 19 similarly interconnected and connected with the remaining of the controllers 25. Thus the operation of either controller 25 will serve to put in motion or to bring to a state of rest any of the motors with which it is connected. These connections between the controllers and the motors are conventional, and their illustration is sufficient description.

Interior to the car A there is carried a gage 26, which is connected to the chamber B for the purpose of indicating the internal pressure therein.

At the stern of a car A there is mounted rudder 28, which is swingably supported on a vertically disposed shaft 29 mounted at the rear of the car. This rudder is formed with a transverse portion 30, to which there connects a cable, the latter winding on a drum 32 operable by a pilot wheel 30 for the purpose of operating the rudder one side or the other from a straight course.

The ship is caused to move forward by the operation of the propellers 6 and fans 9, the latter intaking air through the openings 8 and ejecting it in a stream from the smaller ends of the tubular members 3, such streams of air serving to drive the chamber B forward and with it the car A. At the same time the operation of propellers 6 serve to draw the ship forward and the blast from these propellers is ejected through the smaller ends of the tubular members 3, co-operating with the blasts from the fans to assist further in moving the ship forward. Since the fans 9 and the propellers 6 are under the control of one of the controllers

25, they will operate only when the controller is in the position permitting them to operate. When the said controller is turned to the off position, the motors driving these fans and propellers are rendered inert.

In the event that it is desired to raise the ship, the controller controlling the motors 19 is operated, at which time the propellers 20 are put in motion and serve to draw the chamber B upward, the blasts from the said 75 propellers being ejected through the smaller ends of the tubular members 16 to assist in the raising operation.

Likewise, when it is desired to lower the ship, the controller controlling the motors 80 14 is operated to put the propellers 15 in motion, these propellers then serving to draw the chamber downward and ejecting their blasts through the upper or smaller ends of the tubular members 11.

In the event that it is desired to use heated air in place of a light gas, provision may be made for electrically heating the air by means of electric heaters 37, the latter receiving current from the generator 22 over 90 the wires 34 and 36 and their attendant controlling means 35, as illustrated in Fig. 2.

From the foregoing description and the accompanying drawings, it is believed that a clear enough understanding is to be had 95 to render further description unnecessary.

I claim—

1. In an airship, a buoyant chamber, a plurality of tubular members mounted on the buoyant chamber, the said tubular members being of tapering shape, a rotatable shaft mounted in each tubular member adjacent its larger end, a propeller carried by each shaft at one end, a driving-motor exterior to the tubular member and carried 100 thereby and operatively connected to the propeller shaft therein, and a centralized control for said motors whereby the propellers in certain tubular members may be operated for the purpose specified.

2. In an airship, a buoyant chamber, a plurality of tapering tubular members mounted on the buoyant chamber and disposed in direction of the length of the latter, a plurality of tapering tubular members 115 also mounted on the buoyant chamber but right-angularly disposed with reference to the longitudinal axis of said buoyant chamber, certain of the right angularly disposed tubular members having their larger ends 120 disposed at the bottom of the buoyant chamber, the remainder of said members having their larger ends disposed at the top of said chamber, a rotatable shaft mounted in each tubular member adjacent 125 the larger end, each shaft being axially aligned with its tubular member, a propeller carried by the shaft in one end,

a driving-motor supported adjacent each tubular member and in close proximity to the shaft therein, positive driving connection between each motor and its attendant propeller shaft, and a centralized control for said motor whereby the propellers in all the tubular members may be put in motion

or only those in corresponding tubular members, so that the buoyant chamber may be elevated or lowered or driven forward as 10 herein shown and specified.

In testimony whereof I affix my signature.

GEORGE F. OCHS.
